(57) **CLAIM**

I claim the ornamental design for a school supply container, as shown and described.

DESCRIPTION

FIG. 1 is a top view of a school supply container;

FIG. 2 is a bottom view of the school supply container shown in FIG. 1;

FIG. 3 is a front view of the school supply container shown in FIG. 1;

FIG. 4 is a back view of the school supply container shown in FIG. 1;

FIG. 5 is a left view of the school supply container shown in FIG. 1; and,

FIG. 6 is an isometric view of the school supply container shown in FIG. 1.

The broken lines showing portions of the school supply container in FIGS. 1–6 are for illustrative purposes only and form no part of the claimed design.
